Primary Examiner — Karen E Kearney*(74) Attorney, Agent, or Firm* — Cantor Colburn LLP(57) **CLAIM**

The ornamental design for a display screen or portion thereof with graphical user interface, as shown and described.

DESCRIPTION

The FIGURE is a front view of a display screen or portion thereof with graphical user interface showing our new design. The broken lines illustrating portions of the display screen or portion thereof with graphical user interface are for environmental purposes only and form no part of the claimed design. The broken lines illustrating the text, numbers and graphical elements form no part of the claimed design.
